ARTIFICIAL LURE

John J. Bates, Detroit, Mich.

Application May 14, 1951, Serial No. 15,177

Term of patent 14 years

(Cl. D31—4)

To all whom it may concern:

Be it known that I, John J. Bates, a citizen of the United States, residing at Detroit, in the county of Wayne and State of Michigan, have invented a new, original, and ornamental Design for an Artificial Lure, of which the following is a specification, reference being had to the accompanying drawing, forming a part thereof, in which:

Fig. 1 is a side elevational view of an artificial lure showing my new design;

Fig. 2 is a top plan view of Fig. 1;

Fig. 3 is a front elevational view of Fig. 1; and
Fig. 4 is a rear elevational view of Fig. 1.

I claim:

The ornamental design for an artificial lure, substantially as shown.

JOHN J. BATES.
